[57] ABSTRACT

Polynuclear aromatic hydrocarbons, and other aromatic compounds and organic sulfur and nitrogen compounds are removed as impurities from petroleum streams by extraction with Cr⁺⁺⁺ in a solution of acetone, methanol or ethanol wherein the metal ion complexes with the impurities and is withdrawn with the metal salt solution.

1 Claim, No Drawings

PURIFICATION OF A HYDROCARBON STREAM WITH CR⁺⁺⁺ IONS IN SOLUTION

BACKGROUND OF THE INVENTION

This invention relates to the removal of impurities from petroleum fractions and more particularly relates to the removal of polynuclear aromatic hydrocarbons, sulfur compounds and nitrogen compounds as impurities from hydrocarbons.

The problem of nitrogen and sulfur removal is particularly important in the petroleum industry. Sulfur occurs, generally, in the form of mercaptans, sulfides, disulfides, thiophenes, benzothiophene, and dibenzothiophene. Nitrogen compounds are usually present as heteroatomic organic compounds, such as pyridines, pyrroles, quinolines, pyridines, cyclopentaquinolines, indoles, carbazoles, pyrroloquinones, etc.

These nitrogen and sulfur compounds adversely affect many of the important refining processes. They are believed to reduce the activity of cracking or hydrocracking catalysts because of their polarity and basicity. They are also suspected of being involved in gum formation, color formation, odor and poor storage properties of fuels.

The polynuclear aromatics, besides being carcinogenic, appear to be color precursors and hence their presence also has bearing on color and color stability problems of lubricating oils.

SUMMARY OF THE INVENTION

In accordance with the present invention the above difficulties can be overcome by extracting the polynuclear aromatic hydrocarbons as well as other aromatic compounds, organic sulfur and organic nitrogen compounds from various hydrocarbon streams by means of solutions of metal ions. The petroleum fractions containing the impurities are contacted with the salt solutions whereby metal complexes form which can be removed with the solvent phase. Many metals and many solutions are effective but the transition metals, Fe⁺⁺⁺, Cu⁺⁺, and Cr⁺⁺⁺ as well as Li⁺ are most effective. The most effective solvents are ethanol and acetone.

Such extraction systems are advantageous because of the low cost of the raw materials, because the solvent and metal salt are recoverable and the use of a simple counter-current extraction unit employing recycle will drive the system to completion.

PREFERRED EMBODIMENTS

Feed streams suitable for use in this invention include any type of petroleum stream, e.g. light fractions such as naphthas, lubricating oil fractions, and heavy fractions such as petroleum residua and tars, in short, any hydrocarbon stream containing polynuclear aromatic hydrocarbons, and/or nitrogen and sulfur compounds.

The invention is particularly directed to the removal of impurities, particularly nitrogen and sulfur impurities from the above streams by the use of solutions of metal salts. Suitable metal salts include those of Groups IB, IIB, VIB, and VIII of the Periodic System (E. H. Sargent and Company, 1952) and lithium, e.g. Cr(NO₃)₃, FeCl₃, nickelous acetate, nickelic acetate, Ca(NO₃)₂, AgNO₃, HgNO₃, and LiBr.

Suitable solvents include any oxygenated and/or nitrogen based solvents, i.e. any highly polar solvent, e.g. water, acetic acid, acetone, ethyl alcohol, methyl alcohol, tetrahydrofuran, furan, and peracetic acid. Water may be mixed with the solvent in proportions of from 100 parts solvent to 1 of water to 1 part solvent to 3 of water.

The preferred metal ions are Fe⁺⁺⁺, Cu⁺⁺, Cr⁺⁺⁺, and Li⁺. The preferred solvents are methanol, ethanol, and acetone.

The solvent to hydrocarbon feed ratio may vary from 1:100 through 1:1 to 10:1.

The process is independent of pressure and therefore is best carried out at atmospheric pressure unless some specific reason dictates higher pressures. The temperature chosen will also, in general, be room temperature, although higher tem-

peratures may be used. In general, complex formation of polynuclear aromatic hydrocarbons with the salts will be promoted by room temperature and slightly above. Complex formation of sulfur and nitrogen compounds may in some instances be favored by higher temperatures.

The following examples are presented as specific embodiments of the invention but without any intention of limiting the invention thereto.

EXAMPLE 1

To an aromatic sieve obtained by passing a light petroleum fraction through a 5 Angstrom molecular sieve was added 1.0 ppm 3,4-benzpyrene (C¹⁴ labeled). Separate 100 ml samples of this mixture were extracted with various salt solutions and the amounts of benzpyrene determined by C¹⁴ counting. The following results were obtained:

5	Salt	Solvent	% 3,4 Benzpyrene Removed				
			24 Hr.	48 Hr.	72 Hr.	96 Hr.	166 Hr.
20	Cr(NO ₃) ₃	H ₂ O	1			0	
	FeCl ₃	CH ₃ COCH ₃		25		28	
				24			
25	Cr(NO ₃) ₃	CH ₃ COCH ₃		60			
	Ni(OAc) ₂ *	CH ₃ CH ₂ OH		18			
	LiBr	CH ₃ COCH ₃		38		35	
	LiBr	Tetra-					
		hydrofuran		61		9	
30	Ni(OAc) ₃	CH ₃ COCH ₃			36		
	AgNO ₃	Furan		25		8.3	
							(water added)
	AgNO ₃	Acetone		42			11
	Cu(NO ₃) ₂	CH ₃ COCH ₃		72			
				64			
35	Cr(NO ₃) ₃	CH ₃ COCH ₃		58			
	Cu(NO ₃) ₂	CH ₃ CO ₂ OH		17			
	FeCl ₃	CH ₃ CH ₂ OH		15			
	Ni(OAc) ₂ *	CH ₃ CH ₂ OH		18			
	Ni(OAc) ₂	(CH ₃) ₂ CO				36	
	LiBr	CH ₃ CH ₂ OH		8			
40	HgNO ₃	CH ₃ OH	14	19	26		
	FeCl ₃	CH ₃ OH		7			
	FeCl ₂	Acetone		35		34	
	FeCl ₂	CH ₃ OH				5	
	Co(OAc) ₂ *	CH ₃ OH	6	7			
	Co(OAc) ₂ *	Acetone	38	37			
45	Cu(NO ₃) ₂ (green)	Acetone	65	72		85	
	Cu(NO ₃) ₂ (blue)	Acetone	52	63		73	
	Cr(NO ₃) ₃	Acetone	53	58		62	

*OAc = acetate.

The above data show that all the metals listed and all the solvents except water are operable but that Fe⁺⁺⁺, Cu⁺⁺, Cr⁺⁺⁺ and Li⁺ are most effective when used with ethanol and acetone solvents.

EXAMPLE 2

Two percent solutions of each of the four compounds: (A) 1,2-diphenylethane; (B) dibutylmaleate; (C) dimethyl pyridine; and (D) benzophenone were added to the sieve used in Example 1. Twenty-five ml. of each of these solutions were mixed with 25 ml. of various salt solutions and placed in 2 oz. bottles, sealed and shaken for about 12-14 hours on a mechanical shaker for an elapsed time of 48 hours. Five ml. samples were removed by pipette and separated into raffinate and salt phase layers in calibrated graduated flasks. The efficiency of the extraction was calculated by U.V. analysis. The following results were obtained:

1,2-DIPHENYLETHANE

75	Salt	Solvent	% Compound Removed

$\text{Cu}(\text{NO}_3)_2$	Acetone	4.3
$\text{Cu}(\text{NO}_3)_2$	Ethanol	19.1
$\text{Cu}(\text{NO}_3)_2$	Methanol	8.6
$\text{Cu}(\text{NO}_3)_2$	H_2O	12.8
$\text{Cr}(\text{NO}_3)_3$	Acetone	0.0
$\text{Cr}(\text{NO}_3)_3$	Ethanol	23.0
LiBr	Acetone	0.0
LiBr	Ethanol	16.8
FeCl_3	Acetone	19.1
FeCl_3	Methanol	8.1
FeCl_3	Ethanol	26.2

FeCl_3	Acetone	77.9
FeCl_3	Ethanol	78.2

5 The above data clearly show that 1,2-diphenylethane is most efficiently removed by the FeCl_3 - ethanol system but can be removed by all the systems tried except $\text{Cr}(\text{NO}_3)_3$ - acetone and LiBr - acetone.

10 Dibutylmaleate is removed by all the systems tried but most effectively by LiBr - ethanol and FeCl_3 - ethanol. $\text{Cu}(\text{NO}_3)_2$ - H_2O system is least effective.

15 Dimethylpyridine is effectively and efficiently removed by all the systems tried including aqueous systems.

Benzophenone is removed by all systems tried.

15

EXAMPLE 3

Hydrocarbon solutions of thiophene and dibutyl sulfide were extracted, with various salt solutions and the percent sulfur removed was determined by the Dohrmann microcoulo-meter. The following results were obtained:

	Compound	Salt	Solvent	% S Removed
25	Thiophene in Octane	NaI	Acetone	33.7
	Thiophene in Benzene	$\text{Cu}(\text{NO}_3)_2$	Methanol	23.8
	Thiophene in Benzene	$\text{Cu}(\text{NO}_3)_2$	Ethanol	23.8
	Thiophene in Raffinate ¹	$\text{Cu}(\text{NO}_3)_2$	Acetone	43.7
30	Thiophene in Raffinate ¹	$\text{Cu}(\text{NO}_3)_2$	Acetone	45.6
	Thiophene in Benzene	LiBr	Acetone	19.0
	Thiophene in Benzene	LiBr	Acetone	24.4
	Thiophene in Benzene	$\text{Cu}(\text{NO}_3)_2$	Acetone	52.1
	Thiophene in Benzene	LiBr	Acetone	55.3
	Dibutyl Sulfide in Benzene	$\text{Cu}(\text{NO}_3)_2$	Acetone	36.4
	Dibutyl Sulfide in Sievate ¹	$\text{Cu}(\text{NO}_3)_2$	Acetone	52.0
35	Dibutyl Sulfide in Sievate ¹	$\text{Cr}(\text{NO}_3)_3$	Ethanol	26.0
	Thiophene in Sievate ¹	$\text{Cr}(\text{NO}_3)_3$	Ethanol	42.0

¹The sieve of Example 1.

40 The above data show that sulfur compounds can be satisfactorily removed from hydrocarbon solutions.

The nature and advantages of the present invention having thus been fully set forth and specific examples of the same given what is claimed as new, useful and unobvious and desired to be secured by Letters Patent is:

45 1. A process for removing polynuclear aromatic hydrocarbons, organic sulfur compounds or organic nitrogen compounds from any hydrocarbon stream, which comprises contacting said stream with Cr^{+++} ions in a solution of acetone, 50 methanol or ethanol.
